H. O. Perry,

Machine Gearing.

No. 66,251.

Patented July 2, 1867.

United States Patent Office.

HORATIO O. PERRY, OF BUFFALO, NEW YORK, ASSIGNOR TO HIMSELF
AND JOHN D. SHEPARD, OF THE SAME PLACE.

Letters Patent No. 66,251, dated July 2, 1867.

IMPROVED HOISTING MACHINE FOR VESSELS.

The Schedule referred to in these Letters Patent and making part of the same.

TO ALL WHOM IT MAY CONCERN:

Be it known that I, HORATIO O. PERRY, of the city of Buffalo, in the county of Erie, and State of New York, have invented certain new and useful improvements in Machines for Hoisting and Lowering Lading from and into the Holds of Vessels; and I hereby declare that the following is a full and exact description thereof, reference being had to the accompanying drawings, in which—

Figure 1 is a side elevation.

Figure 2 is a cross-section of the shafting on the line A B.

Figure 3 is an end elevation of the friction-wheel and brake.

Like letters indicate corresponding parts in all of the figures.

My invention consists in a line of shafting composed of sections joined together with universal and extensible joints, when employed in combination with suitable appurtenances for hoisting lading from the holds of vessels or lowering into the same, said shafting being arranged in a line over the deck, hatchways, and longitudinally of the vessel, and connected with and driven by an engine on board the same, the object of said combination of mechanism being to apply steam power to the elevating and lowering of the freight by means of suitable apparatus driven by and from said line of shafting, the peculiar construction of which, by the adaptation of the jointed sections to the springing or curvature of the vessel under an unequal disposition of her lading, enables such a line of shafting to be extended from stem to stern, and kept in motion by the engine without binding and heating of the journals or other difficulty, which would not be possible with a continuous shaft.

My invention is specially designed for use on that class of vessels employed for carrying freight on lake and shallow waters, denominated "propellers," which, to enable them to enter shallow harbors and rivers, are built without much depth of hold, and of great length, in order to give sufficient carrying capacity. In consequence of this construction they are more liable to spring or be deflected from a true line than vessels of greater depth of hold; and this deflection occurs to the greatest extent while taking and discharging cargo from the irregular disposition of the weight thereof before the vessel is trimmed. So great is the extent of this deflection that it is impossible to extend an unbroken line of shafting along the deck of such vessels for the purpose of applying the power of the engine to the labor of discharging and taking on cargo, and have the same remain in working condition; and the demand for performing this labor in the shortest possible time, so that quick trips may be made, has necessitated my invention, which affords an effectual remedy.

As represented in the drawings, A A and D D are the sections of a line of shafting extended from the vicinity of the engine, which is usually near the stern of the boat, to the bow. This shafting is usually hung in brackets attached to the upper deck over the hatchway; or it may be supported on stanchions M M, or in any other suitable manner. The section A A is provided with a crank for connecting it with the engine by means of a pitman, so that it may receive rotary motion; or it may be driven in any other manner. Each section is jointed to the next by means of the coupling B C, usually called a universal joint, or by any similar coupling capable of allowing flexion in every direction from a straight line. The section A A is connected with the part B of the coupling, so as to allow it to slide endwise therein, and thus extend or diminish the length of the shafting, according to the curvature which the vessel may assume. A feather fitted to the shaft, and working in a groove in the sleeve, (as shown in fig. 2,) so connects the sections that they revolve together as one shaft. The same form of connection is employed in the coupling at each joint, so that the entire line is capable of flexion and extension or contraction, according to the variations occurring in the form of the vessel. This line of shafting is employed to raise and lower through the hatchways tables carrying the lading, which are connected by ropes, or in any suitable manner, with a windlass, L, on shaft G, which is also provided with a friction-wheel, F, which receives its motion by contact with the friction-pulley E on the shafting. The axle G has sliding bearings, so that, by means of the lever J J, fig. 3, the wheel F may be held in contact with the driving-pulley E as long as motion is required, and quickly stopped by reversing the lever, which removes it from the driving-pulley, and holds it against the stationary friction-brake or shoe K, by which its motion is arrested.

As many of these hoisting machines as there are hatchways, or as are required for other purposes, are pro-

vided, each driven by a friction-pulley on the shafting, and each working independently of the others, so that hoisting or lowering may be going on at the different hatchways, as required, by taking motion, when needed, from the line of shafting, which revolves steadily and constantly the meanwhile. This line of shafting may be driven from the main engine, or by a donkey engine, and not only saves a large amount of manual labor and time, but is applicable to many other useful purposes, such as weighing anchor, and driving bilge or other pumps located at the bow or other part of the vessel, which is effected by suitable connections for transmitting the motion of the shaft. The last-named use is often of the greatest importance when a vessel trims by the head, or when injured and leaking in the forward portion of the hull.

What I claim as my invention, and desire to secure by Letters Patent, is—

Forming a line of shafting in sections A D, connected by variable and extensible couplings B C, for use on ship-board, constructed, arranged, and operating substantially as set forth.

I also claim, in combination therewith, the friction-pulley E, wheel F, lever J, and brake K, arranged and operating substantially as set forth.

HORATIO O. PERRY.
